UNITED STATES PATENT OFFICE

GUY G. GRAHAM, OF KANSAS CITY, MISSOURI

CANINE NASAL IRRIGATOR

Application filed October 29, 1928. Serial No. 315,689.

This invention relates to canine nasal irrigators and the object is to produce a device of this character by which the nasal passages and sinuses in the head of a dog can be efficiently treated, a further object being to produce a device of simple and inexpensive construction and which has a nozzle of shape which will accommodate itself to the muzzle of most any dog regardless of size.

As far as known no effective device of the character mentioned has been known, as to irrigate the nasal passages and the sinuses in the head of a dog has always been a difficult undertaking as the nose is extremely sensitive at the point where the nasal cavity opens. However, the muzzle of a dog is comparatively non-sensitive, and with this knowledge in view it has been found that by a nozzle shaped and of size to receive and not apply direct pressure at the sensitive point of the nose but apply such pressure on the muzzle as a whole, it is feasible and in fact easy to inject medicinal substances in liquid suspension into the nasal cavity.

Accordingly I have provided an irrigator having a nozzle which will completely encase the nose without applying pressure on the sensitive part thereof, and which has been used successfully on a large number of dogs, and in order that the invention may be fully understood reference is to be had to the following description and to the accompanying drawing; the novel features being set forth in the appended claim.

Referring now to the drawing in detail, Figure 1 is a perspective view of the device as applied in operative position to a dog.

Figure 2 is a central vertical longitudinal section of the device.

Figure 3 is a front view of the nozzle of the device.

In the said drawing, 1 indicates a compressible bulb of rubber or the like having a tubular neck portion 2 to be fitted upon the stem 3 of a nozzle of metal or its equivalent, the stem preferably having an external bead 4 to guard against accidental detachment from the neck of the bulb. The stem is also provided with a passage 5 establishing communication between the bulb and the nozzle

6 which is of generally conical form and at its front end or edge has a flaring mouth 7. The front end of the nozzle as viewed in side view, is bowed forwardly approximately at its horizontal center and from said point 55 slopes downwardly and rearwardly at a comparatively sharp angle, and upwardly and rearwardly from said point at a very slight angle. As a result the top of the nozzle projects forwardly a greater distance from the front end of the bulb than the bottom of the nozzle, so that the upper portion of the nozzle can engage the muzzle a substantial distance rearward of the sensitive point of the nose of the dog, the receding or shorter lower portion of the nozzle at the same time engaging the muzzle of the dog below the nostrils and above the mouth. The protruding of the side portions permits the nozzle to engage the side portion of the muzzle beyond the sides of the nostrils so that the latter may be completely enclosed by the nozzle, it being noted by reference to Figure 3 that the lower portion of the nozzle is approximately horizontal and the upper portion at the center is somewhat pointed so that where the muzzle is relatively narrow and hard above and behind the sensitive point of the nose, the nozzle can with slight pressure be caused to engage that portion of the muzzle with a liquid tight joint. At the same time the remainder of the marginal portion of the nozzle in engagement with the relatively soft portion of the muzzle, will receive the major portion of the pressure and complete a liquid tight encasement of the nostrils.

Figure 1 indicates generally the method of applying the device, the operator placing one hand at the back of the head or neck of the animal to prevent him pulling his head back 90 and with the other hand (not shown), holding the device by means of the compressible bulb.

In practice it is customary to first fill the bulb with water and then placing the device 95 as explained to the canine's nose, apply pressure to the bulb to flush out the nasal passages and sinuses. It is then removed and the discharges from the animal's head are carried out mechanically. The bulb is then 100

charged with a suitable solution, such as a bicarbonate of soda solution, and applied as explained in connection with the water, in order that the nasal passage and sinuses may be douched. The device is then withdrawn and as a similar treatment is desirable to inject by the same method, a warm solution of some antiseptic, such as a chlorine solution.

It has been found through the treatment of a large number of dogs that the device is most effective as the treatments can be efficiently made with facility and ease and without subjecting the animal to any pain through undue pressure of the appliance on the muzzle. It will be understood of course that it is possible to slightly modify the device within the spirit and scope of the appended claim.

I claim:

A nozzle for canine nasal irrigators of generally conical form and having a stem communicating therewith and projecting from the apex thereof, the side portions of the nozzle being bowed forward relative to the top portions thereof but at a sharper or more receding angle at the bottom than at the top, the front end of the nozzle chamber being flared relative to the chamber proper; the lower portion of the front end of the nozzle being substantially horizontal and the upper portion of said end of relatively pointed or upwardly tapering form.

In testimony whereof I affix my signature.
GUY G. GRAHAM.
